UNITED STATES PATENT OFFICE.

CHARLOTTE L. GLOSSBRENNER, OF YORK, PENNSYLVANIA.

DOLL.

1,332,825.

Specification of Letters Patent.

Patented Mar. 2, 1920.

Application filed August 23, 1919. Serial No. 319,339.

To all whom it may concern:

Be it known that I, CHARLOTTE L. GLOSSBRENNER, a citizen of the United States, residing at York, in the county of York 5 and State of Pennsylvania, have invented new and useful Improvements in Dolls, of which the following is a specification.

This invention relates to improvements in dolls of that general type wherein the 10 trunk and limbs, constituting the body, are stuffed and the limbs are connected to the trunk by joints of flexible and continuous character, that is to say, joints which may be termed "impositive" in the sense that 15 they are devoid of mechanical connections such as balls and sockets, wires, hinges, or the like.

The greatest value in point of utility, that 20 is as regards the pleasure or enjoyment afforded by the toy, attaches to dolls which are light in weight, not readily destroyed, and may be dressed or clothed. Doll bodies of the character referred to have been developed with this fact in view and have the 25 advantages of being unbreakable, of having an outline or figure which is substantially as permanent as that of any jointed doll whose body is made of rigid material, and of being lighter in weight, size for size, 30 than most doll bodies of rigid material, either breakable or unbreakable. As regards clothed or dressed dolls, the best results are realized when the doll body may be arranged in various positions and closely 35 or substantially simulates the infant form. This simulation may, as regards the form of the body members, *i. e.*, the trunk and limbs, be readily secured in those constructions where the doll body (either as an 40 entirety or as to its several members) is of rigid material and is produced by molding or otherwise by methods employing dies, subject, however, to the limitations that such doll bodies are either devoid of flexible 45 joints between the body members, or, if having such joints, require therefor mechanical expedients which impair the naturalness and grace of the outline as an entirety, which produce awkward and stilted 50 postures and which do not permit ease of relative movement between the body members. In the case of dolls having stuffed bodies the ordinary mechanical agencies and methods for producing the desired simulation of the infant form are, of course, not

available and there are practical difficulties which have proved serious obstacles to the results sought, especially in contemplation of stuffed dolls having flexible jointure between the limbs and trunk where the joints should have relative ease of action and where the naturalness of effect should be carried out in the joints as well as in the form of the body members. The efforts which have heretofore been made to overcome these difficulties have, so far as I am aware, been only partially successful—that is to say, the attainment of some advantage of structure or utility was attended by the sacrifice or impairment of some other advantage of material value in the general scheme of construction or use. 60 65 70

The principal object of the present invention is to provide, in a doll construction, a stuffed body which combines the advantages 75 of rigid bodies and of stuffed bodies as heretofore known and which has several advantages not possessed by either and contributing materially to the utility of the toy. Stated more specifically, this object 80 is to provide a stuffed doll body which may be practically and economically manufactured; which, having flexible impositive jointure between its members, closely simulates the infant form, may be arranged in 85 various postures, conforming to natural postures and in which the simulation of the infant form, as in those postures, is maintained; and which may be manipulated to produce relative movements between the 90 body members with resultant effects similar to the effects produced by normal corresponding movements of the body members of an infant, for example, the effect of walking. 95

The body of the doll is composed of a casing of textile fabric of any of the kinds ordinarily employed and a filling of soft resilient material such as cotton or wool which may be packed to the density desired; and with the stated objects in view the invention consists generally in the novel structural details of the fabric casing and also in the combination with a casing having such details of a filling of soft resilient material whose density is varied at different parts of the body in such manner as to secure its coöperation with the casing in the provision of flexible jointure between the body members. 100 105 110

In dolls of the type to which the invention relates the utility is enhanced by providing a hollow head of rigid, preferably unbreakable, material which has the advantages, as compared with stuffed fabric material, of being adaptable to a more life-like representation of the features and of being readily cleaned.

A further object of the present invention 10 is to provide a doll having a body and a head, both of the character stated, wherein there is a non-accessible and permanently secure union or connection between the head and the body and any liability of the stuffing 15 of the body, to become displaced within the hollow head (in consequence of the density with which the stuffing may be packed and also of the more or less frequent and severe usage which the toy may be given) is eliminated; and with this object 20 in view the invention further consists in certain novel structural details of the means of connection between the body and the head according to which the securing elements 25 are concealed and are associated with a web which constitutes a part of the connection and acts to substantially close the neck portion of the head and to receive the end thrust or pressure of the somewhat densely packed stuffing.

A doll structure in which the features of the invention are incorporated is illustrated in the accompanying drawing, wherein:—

Figures 1 and 2 are front and side elevations showing the doll in a standing posture;

Fig. 3 is a side elevation showing the doll in a sitting posture;

Fig. 4 is a detail vertical section on the line 4—4 of Fig. 1;

Fig. 5 is a detail horizontal section on the line 5—5 of Fig. 1;

Fig. 6 is a detail vertical section showing the means of connection between the body and the head;

Fig. 7 is a detail horizontal section on the line 7—7 of Fig. 6;

Figs. 8 to 11 are developed views showing the different parts of the fabric casing.

Similar characters of reference designate corresponding parts.

The doll body is composed of a trunk 1, and leg members 2 and arm members 3 connected to said trunk. Said body is also connected to a head 4. The body construction consists of a casing of suitable fabric and a stuffing of cotton or wool or similar resilient material which may be packed to the desired density mechanically to distend the casing and give it a permanent form.

According to the invention, the fabric casing consists of sections stitched together and of such form and relation that, with appropriate regulation of the density of the co-operating stuffing, the members 1 and 3 have

a flexible jointure with the trunk 1 which permits of a relative freedom of movement of said members, and the body closely simulates the infant form, as regards its postures and its movements, and its form in any posture or movement. The close similitude to the infant form will be apparent from a consideration of Figs. 1 and 2 from which it will be noted that the trunk has normal belly, back and hip curves, that the abdominal part is of normal form and location relatively to the hips and the legs, that at the back of the trunk there is simulation of the buttocks, that the arms and legs are of normal shape and proportion, that the continuous jointure between the legs and the trunk is such as to carry out the similitude to the hips, groins and crotch or genital area, and that the continuous jointure between the arms and the trunk is such as to carry out the similitude to the lines of the clavicle and the shoulder curves.

The sections of the fabric casing whereby the body has the characteristics of appearance and action, above pointed out, are provided in duplicate, the form of each of the duplicated sections being shown in Figs. 8 to 11, respectively. The section shown in Fig. 8 combines integrally one of the back halves 5 of the trunk portion and the outer half 6 of either of the leg portions; the section shown in Fig. 9 embodies one of the front halves 7 of the trunk portion; that of Fig. 10 the inner half 8 of either of the leg portions; and that of Fig. 11 either half 9 of either of the arm portions.

In Figs. 1, 2 and 3, in order to avoid multiplication of reference numerals as well as to suggest the relation of the margins of the several sections, all seams are designated by the reference numerals of the connected margins by which they are produced. In the succeeding description margins which are referred to as complements of one another are to be understood as stitched together, thereby forming seams.

Referring to Fig. 8, the back half 5 of the trunk portion has a vertical margin 10 whose shape determines the outline of the center of the back and which complements the similar margin of the companion half 5; the margin 10 may be straight, but it is preferably in the form of a compound curve, very slightly convex, as at 10^a in the upper half of its length and very slightly convex as at 10^b in the lower half of its length. The margin 10 may be said to have its lower termination at a point 10^c at which point it indistinguishably joins a margin 11 formed along an approximately semi-elliptic convex curve whose components preferably lie slightly beyond and adjacent the lines of an imaginary right angle (see dot and dash lines, Fig. 8) extending from about the central point 11^a of the curve 11 and one of

which is taken between said point 11^a and the point 10^c. The part 5 has another vertical margin 12 which at its upper end joins at a right or slightly greater angle a substantially straight margin 13 extending inward and whose shape determines what may be called the clavicular line of the trunk, that is to say, the line between the neck and the shoulder curve. Between the margins 13 and 10 an extension or tab 14 is provided which is used in connection with the union of the doll body and head and, as folded in along a line taken between the points where at it joins the margins 13 and 10 produces one-fourth of the circle of the neck. The vertical margin 12 determines the vertical line of the trunk at either side and is preferably suitably concave whereby when the part 5 is distended to follow the circle of the trunk the vertical side line of the trunk as viewed from the front (see Fig. 1) will be substantially straight; the upper portion of the margin 12 is used in the jointure of the trunk and either of the arms. The margin 12 merges indistinguishably at its lower termination which may be taken as the point 12^a with a slightly convex margin 15 directed at a slight outward angle and whose lower termination may be taken at the point 15^a. The margin 15 is located opposite the margin 11 and since both of these margins are convex the part 5 has its greatest width in the area between them. This portion of increased width gives the prominence characteristic of the hip areas at the sides and adjacent the buttocks, the lines of which are determined by the margins 11 which in the completed fabric extend downward in diverging relation from the point 10^c. The margins 15 determine the lines of the thighs at the front of the legs and at the points 15^a indistinguishably join the margins 16 which determine the front lines of the portions of the legs below the knees and preferably bend inward from the margins 15. The margin 11 has its lower termination at a point 11^b where it forms an approximate right angle with the slightly convex margin 17 whose shape determines the back lines of the calves. It will be noted that the margins 16 and 17 have a converging relation in their lower portions whereby the lower portions of the legs as formed by the parts 6 will have the normal outlines characteristic of infants. The part 6 terminates in a foot portion 6^a whose margins extend from the lower terminations of the margins 16 and 17.

The section 7 shown in Fig. 9 has a vertical margin 18 which is stitched to the similar margin of the companion section 7 and is shaped to produce the vertical outline of the chest and belly at the center of the trunk. The margin 18 is of regular convex curvature throughout its extent, such curvature being accentuated in its lower portion

which bends inward to produce the line of the abdomen as directed toward the crotch or genital area. The section 7 also has a lateral vertical margin 19 which complements the margin 12 of the part 5, its upper portion being used in the jointure of the trunk and either of the arms; the margin 19 has a generally concave curvature whereby as straightened out to match the margin 12 in producing the vertical line of the trunk at the side it will develop across the section 7 the fullness or roundness of the transverse chest and abdominal outlines. The margin 19 at its lower termination 19^a indistinguishably joins a convex margin 20 which is bent inward and meets the lower end of the margin 18 at an angle slightly greater than a right angle; the margin 20 establishes the line of the groin and in the connected relation of the sections extends forward and downward from the point 19^a in diverging relation to the margin 15 which, as stated, determines the line of the thigh at the front of the leg. The section 7 also has an upper margin 21 which complements the margin 13 of the part 5 and which extends inward at a suitable angle from the margin 19. Between the margin 21 and the vertical margin 18 an extension or tab 22 is provided, this extension being functionally the same as the similar extension 14 of the part 5 and, as folded in along a line taken between the adjacent terminations of the margins 18 and 22, producing one-fourth of the circle of the neck. The extensions 22 and 14 are, of course, complementary.

The section 8 shown in Fig. 10 has a margin 23 which complements and is of the same outline as the continuous margins 15 and 16 of the part 6. It also has a margin 24 which complements and is of the same outline as the margin 17 of the part 6. The section 8 terminates at its lower end in a foot portion 8^a which complements the foot portion 6^a. The upper portion of the section 8 has what may be termed a fish-tail outline and includes two oppositely directed parts; one of these, the part 25, lies at the front of the thigh adjacent the groin and has a margin 26 which complements the margin 20 of the part 7, and the other, the part 27, lies at the rear of the thigh adjacent the crotch and has an outer margin 28 which complements the margin 11 of the part 5 and an inner margin 29 which complements a similar margin of the companion part 8. The margin 28 forms substantially the same angle with the margin 24 as does the margin 11 with the margin 17. The margins 29 and 26 extend convergingly inward from the respective margins 28 and 23 with which they form acute angles and at their inner ends meet at a point 30 at which they form a right angle, more or less. The point 30 lies at the center of the front of the crotch and

is the common meeting point of the trunk front seam 18, the crotch seam 29 and the 5 groin seams 26—20. The crotch seam 29 lies in the same vertical plane as the trunk front seam 18 and back seam 10 and extends centrally of the buttock portions between the point 30 and the point 10^c. Thus, the point 10^c is the common meeting point of the crotch seam 29, the trunk back seam 10 10 and the two buttock seams 11—28, the angle of which is bisected by the seam 29. The point 19^a is the common meeting point of the trunk side seams 12—19, the groin seams 20—26 and the thigh seams 15—23. The 15 seams 17—24 of the calves form regular continuations of the buttock seams 11—28.

The arm section 9 shown in Fig. 11 is of well-known form and needs no special description; in each arm it is complemented by 20 a similar section. Its upper horizontal line complements the upper portion of the margin 12 or 19 accordingly as the section is arranged at the front or back of the arm and hence in adjacency to the part 5 or the 25 part 7.

The fabric casing constructed as above described is mechanically distended by the filling 31 (Figs. 4 and 5) of cotton or wool. Within the trunk, arms and legs, this filling 30 is packed to a certain desired density, which is higher than the density to which it is packed at the joints. In other words, the filling is left somewhat loose at the joints, *i. e.*, between the shoulder seams and adjacent 35 the groin seams 20—26 whereby the pendant limbs may swing or be bent relatively to the trunk with a certain measure of freedom. Hence, by grasping the doll at its shoulders and with appropriate manipulation in the obvious manner the legs may be made to pursue the normal motions of walking. The doll may also either in a sitting or standing position be arranged in various 40 ways simulative of natural postures. The relative looseness of the filling at the joints is suggestively indicated in Figs. 4 and 5, the section of the former being taken through the trunk and one of the legs and of the latter through the trunk and one of 45 the arms.

The head 4 of rigid material is of the known construction adaptable to dolls of the 50 stuffed body type and has its cylindrical neck portion 32 provided with a circumscripting flange 33 which serves for its attachment to the body.

The invention further proposes an improvement in the means of connection between the head 4 and the trunk, the details 55 of which are shown in Figs. 6 and 7, in which improvement the extensions 14 and 22 are utilized. These extensions as stitched together and bent inward to determine the circle of the neck are fitted over the neck portion 32 and secured adjacent the flange 33

by an encircling retaining strip 34 which may be made in one piece or in halves secured at their ends and which has a close or taut fit just above the flange 33. The extensions 14 and 22 are of such depth that 70 they may be turned in under the flange 33 in a common plane and secured together along the circle of their edges by a drawstring 35 or otherwise. As thus arranged and secured the extensions 14 and 22 provide 75 a taut web or diaphragm 36 across the lower end of the hollow neck portion 32 which serves as a physical barrier against the displacement of the filling material into the hollow head 4, its effectiveness for this purpose being unimpaired by the comparatively small opening at the center where the drawstring 35 is arranged. The web 36 thus maintains the density of the filling material in the trunk and cooperates with the flange 80 33 to prevent any relative inward displacement of the neck portion 32 in the neck opening of the fabric casing. Apart from these advantages, the connection described is of value in maintaining the head firmly in its 85 intended position relatively to the body, that is to say, in maintaining the alinement of the head and the trunk.

The connection shown in Figs. 6 and 7 may, if desired, be used for associating the 90 rigid forearm and hand elements 37 with the stuffed arms.

Having fully described my invention, I claim:—

1. In a doll of the type set forth, a fabric 100 casing comprising two sections, each of which embodies half of the back of the trunk and the outer half of a leg, and being stitched together along a vertical line coinciding with the center of the back of the 105 trunk, and two sections, each embodying half of the front of the trunk, and being stitched together along a vertical line coinciding with the center of the front of the trunk and stitched to the trunk portions of the first- 110 named sections along vertical lines intermediate said above-mentioned lines of stitching, and two sections, each embodying the inner half of the leg and wing portions arranged for connection to one another along 115 a line coinciding with the crotch and which extends between the lines of the center of the back and front of the trunk and to the adjacent sections of the two respective pairs of sections first named along lines coinciding 120 with the buttocks and the groins, the inner half of the leg being stitched to the companion outer half of the leg along lines which extend from said intermediate vertical lines and along lines which form continuations of the lines of the buttocks.

2. In a doll, the combination of a stuffed body member made in sections joined together to delimit an opening, a rigid member fitted in said opening and having a cir- 130

cumscribing flange, said sections having tabs joined together and turned in under said flange, a retaining strip closely encircling said tabs and rigid member adjacent said flange and means associated with the turned in portions of said tabs for holding them taut in a common plane under said flange.

In testimony whereof I have hereunto set my hand in presence of two subscribing witnesses.

CHARLOTTE L. GLOSSBRENNER.
